United States Patent Office

Des. 228,123
Patented Aug. 14, 1973

228,123

BOTTLE

Joachim Besier, an der Favorite 6, 6500 Mainz, Germany

Filed Nov. 9, 1970, Ser. No. 25,896

Term of patent 14 years

Int. Cl. D9—01

U.S. Cl. D9—127

Fig. 1

Fig. 2

FIG. 1 is an elevational view of a bottle showing my new design, the opposite side being the same in appearance as the side shown, and

FIG. 2 is a top plan view thereof.

I claim:

The ornamental design for a bottle, as shown and described.
